UNITED STATES PATENT OFFICE.

GUSTAV GOLDMAN, OF BALTIMORE, MARYLAND.

DESIGN FOR A COAT-PAD.

SPECIFICATION forming part of Design No. 32,553, dated April 17, 1900.

Application filed February 27, 1900. Serial No. 6,761. Term of patent 7 years.

To all whom it may concern:

Be it known that I, GUSTAV GOLDMAN, a citizen of the United States of America, and a resident of No. 2000 McCulloh street, city of 5 Baltimore, State of Maryland, have invented a certain new and original Design for a Coat-Pad, of which the following is a specification.

My new and original design relates to a coat-pad to be used in the manufacture of garments.

Figure 1 is a plan view of the coat-pad. Fig. 2 is an edge view of the pad.

As shown in the accompanying drawings, my design for a coat-pad consists of a pad 15 substantially elliptical in shape and having two angular corners 1 and 2, 1 being acute, and 2 elongated, the center of the pad being thick and of uniform thickness and substantially elliptical in shape and the edge gradually decreasing in thickness from the center 20 ellipse to the exterior edge. At the center of one side, about midway between the ends 1 and 2, there is a slit formed in a broken line

and extending from the outer edge to the edge of the thick portion opposite.

The leading and material feature of my design consists of the elliptical shape of the pad, having one acute point and one elongated point, the pad being thick in the center and beveled all around the edge from the thick 25 portion to the extreme edge and having a slit formed in a broken line extending from the edge of one side midway between the points 1 and 2 to the center of the side of the elliptical high portion.

Having described my invention, what I claim as new, and desire to secure by Letters Patent, is—

The design for a coat-pad as herein shown and described.

Signed by me at Baltimore city, State of Maryland, this 16th day of February, 1900.

GUSTAV GOLDMAN.
